[57] CLAIM

The ornamental design for a vehicle tire, as shown and described.

DESCRIPTION

FIG. 1 is a perspective view of a vehicle tire showing my new design, it being understood that the tread pattern and side wall portion continue throughout the circumference of the tire shown schematically in solid lines, the opposite side being substantially the same as that shown.

FIG. 2 is an enlarged fragmentary developed plan view of the tread pattern thereof.

FIG. 3 is a cross-sectional view taken along line 3—3 of FIG. 2.

FIG. 4 is a fragmentary cross-sectional view on an enlarged scale taken along line 4—4 of FIG. 2.

FIG.1

FIG.4

FIG. 2

FIG. 3
